UNITED STATES PATENT OFFICE.

ROBERT M. KEATING, OF SPRINGFIELD, MASSACHUSETTS.

LUNCH-CHAIR.

1,344,901.

Specification of Letters Patent. Patented June 29, 1920.

Application filed February 14, 1918. Serial No. 217,229.

To all whom it may concern:

Be it known that I, ROBERT M. KEATING, a citizen of the United States of America, residing in Springfield, in the county of 5 Hampden and State of Massachusetts, have invented new and useful Improvements in Lunch-Chairs, of which the following is a specification.

The object of my invention is to provide 10 a superior construction of lunch chair wherein the parts may be more easily kept sanitary than in constructions heretofore known, and wherein the tray and arm rests are firmly held in position and danger of 15 displacement avoided, and wherein the occupant of the chair may be more conveniently and comfortably seated and generally to provide a lunch chair of superior construction and more convenient for use.

20 I accomplish the objects of my invention by the construction herein shown.

In the accompanying drawings in which like characters of reference indicate like parts—

25 Figure 1 is a perspective view of a lunch chair showing a part of its improved construction.

Fig. 2 is a side elevation.

Fig. 3 is a detached view of a longitudinal 30 section of the tray, the tray supporting members being shown in full lines, and

Fig. 4 is a transverse sectional view of the tray and supporting bar.

The construction will be readily understood on reference to the drawings. The chair comprises a suitable frame, the rear legs being extended upwardly above the seat portion to form a part of the back frame, and one of the front legs being projected a short distance above the seat and adapted to form a part of the tray support. An arm rest is arranged at one side and is preferably supported by the framework of the back of the chair. A shelf is arranged 45 below the chair seat, which shelf serves not only as a convenient receptacle for hats and bundles, but also serves to strengthen and brace the chair frame.

The preferred form of tray is provided 50 with downwardly projecting members *m* which engage the supporting bar *h* and to which the parts *m* are secured by means of screws, bolts, rivets or other fastening means. The members *m* may extend from 55 end to end or may comprise short engaging members. The engaging members may be

formed integral with or independently of the tray body. If formed separately they may be attached by electric welding or other convenient means.

60

The arm rest *j* is secured to and supported by the chair back, it being by preference secured to the upwardly projecting back frame and in some instances I employ a bracket *k* to give additional rigidity and 65 support.

The tray supporting member *h* preferably projects beyond the vertical members *a'* and *f*, thus stiffening and supporting the portion of the tray which projects beyond these 70 vertical parts.

A brace member *g* extending from the frame member *d* to the member *f* serves to give added rigidity to the parts,—especially to the vertical member *f* and as the part 75 *g* is located below the level of the lower face of the tray, it in no way interferes with the convenient movement of a wiping cloth completely around the edge of the tray.

I may, in some instances, employ an additional stiffening member *o* between the two vertical tray supports.

I am well aware of the construction shown in U. S. Letters Patent to Berger and Abraham, dated August 6, 1912, No. 1,034,678, for 85 chair and patent to Foster, dated April 21, 1903, No. 726,153, school desk and seat attachment and I make no claim to the constructions therein shown.

This application is in part a division of 90 my Patent No. 1,263,324.

Having therefore described my invention what I claim as new and desire to secure by Letters Patent is:—

1. In a lunch chair, the combination of 95 a suitable frame having a back and substantially vertical front legs, one of such legs extending above the seat portion of said frame, a tray-supporting member mounted on said extended front leg, a tray mounted on said supporting member therefor, and an arm rest secured to said back behind said tray, the construction and arrangement being such that there is a clear space all around the edge portions of both said tray 100 and its support, below as well as above.

2. A lunch chair comprising a suitable frame, one of the front legs thereof being extended upwardly above the seat portion, a vertical supporting member as *f* mounted 110 on the frame of the seat portion, a brace as *g* extending from the back frame to the

member *f*, a tray-supporting member *h* attached to the two vertical supporting members at a point above the horizontal brace *g*, a tray suitably mounted on the supporting member *h*, and an arm rest supported by the back frame and projecting forwardly and outwardly therefrom.

3. A lunch chair having a back with an

arm rest supported therefrom, and provided with a tray, said tray being spaced from and forward of said rest, and constructed and arranged so that there is a clear space all around the edge portions thereof, below as well as above.

ROBERT M. KEATING.
